UNITED STATES PATENT OFFICE.

JOSEPH P. BRYAN, OF BALTIMORE, MARYLAND, ASSIGNOR, BY MESNE ASSIGNMENTS, TO DWIGHT M. LUDINGTON AND A. S. GOLDSBOROUGH, TRUSTEES.

ADDRESSING-MACHINE.

No. 877,400.

Specification of Letters Patent.

Patented Jan. 21, 1908.

Application filed December 14, 1905, Serial No. 291,710. Renewed April 9, 1907. Serial No. 367,220.

To all whom it may concern:

Be it known that I, JOSEPH P. BRYAN, a citizen of Maryland, residing at Baltimore, in the State of Maryland, have invented certain new and useful Improvements in Addressing-Machines, of which the following is a specification.

My invention relates to "printing," but more particularly an addressing machine, and has for its object to provide a machine of this class wherein the name plates of printing surfaces containing the addresses to be printed upon envelops, circulars, etc., are contained in a magazine and from which impressions are made while yet in the magazine through a suitable medium in such manner that the impressions have the appearance of type-writing.

A further object of my invention is to provide an addressing machine wherein the name plates are automatically removed from the magazine and deposited in a receiving magazine after an impression has been made from each name plate.

With these objects in view, my invention consists in the novel construction of the machine, and particularly in the construction for operating the platen, backing up or mounting the name plate from which an impression is to be made in intermittently moving the ribbon or other medium and in withdrawing the name plate and depositing the same in a receiving magazine after an impression has been made from the same.

Referring to the accompanying drawing: Figure 1 is an elevation partly in vertical transverse section through the machine, and Fig. 2 is an elevation partly in vertical longitudinal section through the machine.

Like numerals of reference indicate the same parts throughout the two figures, in which:

1 is the addressing machine which comprises the name plate magazine 2 vertically secured in position to the arm 3 and constructed to hold a number of name plates 3'.

4 indicates the platen which is connected to a link 5 at one end and to the arm 6 of the lever 7 at its other end.

8 indicates the operating lever fulcrumed at 9 and connected to the link 5 by means of a link 10.

Connected to the lever 7 by means of a link 11 is the ejector 12 which is at the bottom of

the magazine 2, and which receives and holds the name plate while the impression is being made therefrom. Arranged in connection with said ejector is a receiving magazine 13 into which the name plate is deposited after impression is made therefrom, and 14 indicates a pawl arranged at the top of said magazine which engages the said name-plate to prevent its return to the name plate magazine and to insure its deposit into the receiving magazine.

It will be noted that the impression may be made through any suitable color vehicle, such as an inked fabric, typewriter ribbon, carbon paper, or the like, and it will be understood that by the term "color vehicle" I mean any material that may be interposed between the printing surface and the platen for the purpose of transferring or reproducing impressions from said printing surface. In the drawing I have illustrated a ribbon 18 similar to the ordinary typewriter ribbon, the same being mounted on spools 15, 16, rollers 17 being arranged below the spools to guide the ribbon under the name plate magazine. On the spool 16 is arranged a ratchet-wheel 19 which wheel is engaged and rotated intermittently by a pawl 20 carried on a lever 21 pivoted at 22 to the base 23 of the machine. Pivoted to said lever 21 below the said pawl is the backing or mounting slide 24 which passes through the name-plate magazine 2 between the name-plate from which an impression is to be immediately made and the next succeeding name-plate, so that when the platen 4 is raised the name-plate is securely backed or mounted within the magazine while the impression is being taken. Journaled on said lever 21 below the backing or mounting slide 24 is a roller 25 arranged to engage a cam 26 on the rear of the platen 4. A leaf spring 27 in engagement with said lever 21 holds said roller normally in contact with said cam as shown in Fig. 2.

Having thus fully described the several parts of my invention its operation is as follows: A number of the name-plates are placed in the name-plate magazine 2. The envelop, circular or other paper or surface to be printed upon is placed on the platen 4. The operating lever 8 is depressed which raises the platen and draws the ejector toward the left (Fig. 1). As said platen is moving upwardly, the roller 25 on the lever 21

follows the cam 26 on the platen 4, by reason of the pressure of the leaf spring 27. This movement of the lever 21 carries the backing or mounting slide 24 through the name-plate magazine, backing up the name-plate for the impression, while the lever moves the pawl 20 under the ratchet wheel 19. When the impression has been made the operating lever is raised which lowers the platen and moves the ejector to the right carrying with it the name plate until same is engaged by the pawl 14 above the receiving magazine 13. The downward movement of the platen and cam 26 forces the lever 21 to the right (Fig. 2) which withdraws the backing or mounting slide 24, allowing the succeeding name-plate to drop into position in the ejector 12, and causes the pawl 20 to move the ratchet wheel 19 and wind the ribbon so as to present a new ribbon surface to the succeeding name-plate.

Having thus fully described my invention, I do not wish to be understood as limiting myself to the exact construction herein set forth, as various slight changes may be made therein which would fall within the limit and scope of my invention, and I consider myself clearly entitled to all such changes and modifications as fall within the scope of the following claims.

What I claim as my invention and desire to secure by Letters Patent of the United States is:

1. In a machine of the character described, the combination of a name plate magazine, a platen movably secured under said magazine, an ejector associated with said platen and moved therewith and arranged to eject said name-plates in said magazine successively, a receiving magazine constructed to receive the name-plates ejected from said first mentioned magazine, a backing or mounting slide arranged to enter behind the name-plate from which an impression is imme-

dately to be made, the movement of said backing or mounting slide being coincident with the movement of said platen, and a color vehicle between said name-plate and said platen, substantially as described.

2. In a machine of the character described, the combination of a magazine arranged to carry a series of name-plates, a platen associated with said magazine, an ejector associated with said magazine and arranged to eject the name-plates from said magazine, a backing or mounting slide associated with said magazine for backing or mounting said name-plates, and a color vehicle arranged between the platen and the name-plates, substantially as described.

3. In a machine of the character described, the combination of a magazine constructed to carry a series of name-plates, a platen associated with said magazine and arranged to be moved against one of said name-plates,

means for ejecting a name-plate from said magazine when said platen is being moved away from a name-plate, and means for backing or mounting one of said name-plates when said platen is being moved toward said name-plate, substantially as described. 70

4. In a machine of the character described, the combination of a magazine arranged to carry a series of name-plates, a movable platen associated with said magazine, an ejector operated by the movement of said platen for ejecting a name-plate from said magazine, and a backing or mounting element operated by the movement of said platen for backing or mounting a name-plate, substantially as described. 75

5. In a device of the character described, the combination of a magazine arranged to carry a series of name-plates, a reciprocating platen associated with said magazine, and means to hold one of said name-plates while an impression is being made therefrom and to eject said name-plate from said magazine, substantially as described. 85

6. In a device of the character described, the combination of a vertically arranged stationary magazine arranged to carry a series of name-plates, a platen associated with said magazine, a backing or mounting device movable through said magazine for backing or mounting a name-plate while an impression is being made therefrom, substantially as described. 90

7. An addressing machine comprising a color vehicle, a magazine to contain a plurality of independent printing surfaces, and means for successively separating each printing surface from those remaining in the magazine and supporting it in a position within said magazine to impart an impression through said color vehicle. 100

8. An addressing machine comprising a stationary magazine for containing a plurality of independent printing surfaces, and automatic means for successively separating each printing surface from those remaining in the magazine, and backing the same in a position to impart an impression while retained in said magazine. 110

9. An addressing machine comprising a stationary magazine for containing a plurality of independent printing surfaces, and a reciprocating slide for successively backing each printing surface in a position to impart an impression while retained within said magazine. 115

10. An addressing machine comprising a stationary magazine for containing a plurality of independent printing surfaces, a backing or mounting slide for successively backing and mounting each printing surface while retained within said magazine, and means for automatically operating said slide. 125

11. An addressing machine comprising a

- color vehicle, a magazine for containing a plurality of independent printing surfaces, means for successively separating each printing surface from those remaining in the magazine and supporting the same within said magazine in a position to impart an impression through said color vehicle, and means for ejecting said printing surface after the printing operation. 5
10. 12. An addressing machine comprising a color vehicle, a magazine for containing a plurality of independent printing surfaces, a backing or mounting slide for successively backing or mounting each printing surface while retained within said magazine and in a position to impart an impression through said color vehicle, and means for operating said slide. 15
13. An addressing machine comprising a stationary magazine for containing a plurality of independent impression surfaces, automatic means for successively backing or mounting each printing surface while retained within said magazine, and means for 20 successively ejecting the name plates from said magazine after the printing operation.
14. An addressing machine comprising a magazine for containing a plurality of independent impression surfaces, a backing or 25 mounting slide for successively backing or mounting each printing surface while retained within said magazine, an ejecting slide, and means for alternately operating said slides. 30
35. 15. An addressing machine comprising a magazine for containing a plurality of independent printing surfaces, a movable platen located beneath said magazine, and an ejector slide operated by said platen.
40. 16. An addressing machine comprising a magazine for containing a plurality of independent printing surfaces, a movable platen located beneath said magazine, an ejector slide, and a pivoted member connecting said 45 ejector slide and said platen.
17. An addressing machine comprising a magazine for containing a plurality of independent printing surfaces, a reciprocating
- platen, and a backing slide working in said magazine and operated by said platen. 50
18. An addressing machine comprising a magazine for containing a plurality of independent printing surfaces, a reciprocating platen, an ejector, and a backing slide, said ejector and backing slide being alternately 55 operated by said platen.
19. An addressing machine comprising a magazine for containing a plurality of independent name plates, a reciprocating platen, a backing slide, a color vehicle interposed 60 between said platen and magazine, and means operated by said platen for imparting movement to said backing slide and said color vehicle.
20. An addressing machine comprising a 65 magazine for containing a plurality of independent printing surfaces, a platen movably mounted with relation to said magazine, and means operated by said platen for successively backing and mounting each printing 70 surface while retained within said magazine.
21. An addressing machine comprising a magazine for containing a plurality of independent printing surfaces, a platen, a color vehicle, means operated by said platen for 75 successively supporting each printing surface in position to impart an impression through said color vehicle, and means controlled by said platen for shifting said color vehicle. 80
22. An addressing machine comprising a magazine for containing a plurality of independent printing surfaces, a color vehicle, means for imparting impressions from said printing surfaces through said color vehicle, 85 means controlled by the impression means for backing said printing surfaces successively in printing position, and means controlled by said impression means for shifting said color vehicle. 90

In testimony whereof I affix my signature in presence of two witnesses.

JOSEPH P. BRYAN.
